UNITED STATES PATENT OFFICE.

WILLIAM J. BOLAND, OF FERRYSBURG, MICHIGAN.

STEAM-ACTUATED VALVE.

SPECIFICATION forming part of Letters Patent No. 234,649, dated November 23, 1880.

Application filed September 3, 1880. (Model)

To all whom it may concern:

Be it known that I, WILLIAM J. BOLAND, of Ferrysburg, in the county of Ottawa and State of Michigan, have invented certain new

5 and useful Improvements in Steam-Actuated Valves; and I do hereby declare that the following is a full, clear, and exact description of the invention, which will enable others skilled in the art to which it appertains to 10 make and use the same, reference being had to the accompanying drawings, which form a part of this specification.

Figure 1 is a perspective view of my improved cut-off mechanism for steam-valves. 15 Fig. 2 is a vertical sectional view of the improved valve cut-off mechanism applied to a steam-cylinder. Fig. 3 is a vertical cross-sectional view of the same. Fig. 4 is a horizontal sectional view on the line $\alpha\alpha$ in Fig. 2; and Fig. 20 5 is a sectional perspective view, showing the valve cut-off mechanism.

Corresponding parts in the several figures are denoted by like letters of reference.

This invention relates to an improved cut-off 25 valve for steam-engines, the construction and operation of which will be hereinafter fully described, and particularly pointed out in the claim.

In the drawings hereto annexed, A represents the steam-cylinder, and B is the valve-chamber. Steam is admitted into the latter through an opening, C, centrally located in the top of said chamber.

D is a piston-valve, which consists of two 35 cylindrical tubes, E E, connected with a stem or shaft, F, and connected by a bar, G, mention of which will be hereinafter made.

H is a chamber located below the piston-valve and above the steam-cylinder, and in 40 which the slide-valve I is placed. The latter consists of a plate, J, provided upon its under side with two recesses, K L, and having an upward-projecting stem, M, fitting or adjusted in a recess, N, in bar G, by the shoulders of 45 which it is alternately reciprocated.

From the chamber H passages O P communicate, respectively, with the ends of the steam-cylinder. Said passages communicate, respectively and alternately, with the exhaust- 50 port Q through the recesses K and L in valve I.

R and S are passages constructed below the

piston-valve and connecting with the exhaust-port Q. The said passages are open for communication with the piston-valve, as hereinafter described.

55

The cylindrical tubes E E of the piston-valve are provided with openings R' R², which, when the valve reciprocates, connect alternately with the exhaust-passages R and S.

T is the piston, which reciprocates in the 60 usual manner in the steam-cylinder. The piston-rod is provided with an arm, U, having an eye or opening, V, which slides over the valve-stem F between two tappets, W W, by which the valve is started in its movements. 65

The operation of the invention is as follows: Steam enters at C, passes down around the bar G into the chamber H, thence under one side of the slide-valve I, according to its location in the chamber H, into the recess K or 70 L, and thence through passage O or P into the steam-cylinder to operate the piston T. The steam drives the piston T to the end of the cylinder A opposite the passage at which the steam enters, and the steam in front of 75

the piston T escapes through the passage which the piston approaches under the slide-valve I and through the recess K or L, as the case may be, into the exhaust-opening Q. The recesses R and S are connected with the ex- 80

haust Q, as shown in dotted lines in Fig. 2. The piston T carries the arm U with it as it is moved, and the eye V of the arm U strikes one of the tappets W and starts the piston-valve D, which is moved until steam from the 85 chamber H can pass through the opening R' or R², as the case may be, to drive the piston-valve D in its proper direction. The shoulders on the bar G strike the stem M of the slide-valve I, and both the slide-valve I and 90 the piston-valve D are driven simultaneously in the same direction.

Having thus described my invention, I claim and desire to secure by Letters Patent of the United States—

95

In a steam-engine, the combination, with the steam-cylinder A, provided with the piston T, having arm U, of the piston-valve D, consisting of the bar G, recessed at N, and having the tubes E E, provided with openings 100 R' R² at opposite ends thereof, the passages R and S, communicating with the exhaust-

opening Q, the chamber H, and the sliding valve I, having stem M and recesses K and L, the said sliding valve I and the piston-valve D both moving simultaneously in the same direction, constructed and operating substantially as and for the purposes set forth.

5 In testimony that I claim the foregoing as

my own I have hereto affixed my signature in presence of two witnesses.

WILLIAM J. BOLAND.
